BY

Geo. P. Kimmel. ATTORNEY.

J.M.D.

UNITED STATES PATENT OFFICE.

GEORGE ERNEST NAGEL, OF GREENVILLE, OHIO.

COMBINED RAIL ANCHOR, CHAIR, AND CUSHION.

Application filed July 24, 1925. Serial No. 45,917.

To all whom it may concern:

Be it known that I, GEORGE ERNEST NAGEL, a citizen of the United States, residing at Greenville, in the county of Darke and State of Ohio, have invented certain new and useful Improvements in Combined Rail Anchors, Chairs, and Cushions, of which the following is a specification.

This invention relates to a combined rail anchor, chair and cushion for use in connection with reinforced concrete cross ties, and has for its object to provide, in a manner as hereinafter set forth, a device of the class referred to, for not only setting up a satisfactory cushion for a track rail, but further anchoring the rail in position with respect to the tie.

Further objects of the invention are to provide, in a manner as hereinafter set forth, a combined rail anchor, chair and cushion for use in connection with reinforced concrete cross ties, and which is simple in its construction and arrangement, strong, durable, compact, thoroughly efficient in its use, conveniently set up with respect to the tie, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:

Figure 1 is a section on line 1—1 of Figure 2, showing the adaptation of a combined rail anchor, chair and cushion, in accordance with this invention, with respect to a concrete cross tie.

Figure 2 is a top plan view of the device showing the adaptation thereof in connection with the tie.

Figure 3 is a section on line 3—3, Figure 1.

Referring to the drawings in detail, 1 denotes a reinforced concrete cross tie provided between its center and each end, only one of the end portions of the tie being shown,

with a wide transverse groove 2 of substantial depth in its top 3. The groove 2 provides what may be termed a pocket or seat.

Mounted in the groove 2 and abutting against the opposed side walls thereof is a rectangular cushioning element 4 constructed of wood. The height of the element 4 is greater than the depth of the groove 2, whereby the element 4 will permanently project above the top 3 of the tie 1. The width of the element 4 is the same as the width of the tie 1, whereby the side edges of said element 4 will be flush with the sides of the tie 1.

Positioned on the cushioning element 4 is a chair member 5 in the form of an inverted channel iron of a length less than the length of said element 4, and the said chair 5 has the sides 6 thereof of a height to enclose the sides of the element 4 and to extend against the sides of the tie 1. When the chair 5 is mounted in position, each of the ends thereof is arranged inwardly with respect to an end of the element 4. The top of the chair 5, between its transverse center and inner end is formed centrally thereof with an opening 7, which registers with an opening 8 formed in the element 4, and extending through said registering openings 7, 8, as well as being embedded in the tie 1, is a vertically disposed anchoring bolt 9 provided at its upper end with a head 10 and having its lower terminal portion threaded, as at 11. Threadedly engaging with the lower end of the bolt 9, as well as being embedded in the tie 1 and flush with the lower face of the latter is a securing nut 12, having positioned thereon a washer 13 of a diameter to project from the nut 12, and the said washer 13 is embedded in the tie body 1.

The track rail, which is indicated at 14, has its web 15 provided with an opening 16. The base 17 of the track rail 14 is mounted on the chair 5, extends transversely thereof and is positioned between the transverse center and outer end of the chair.

The track rail 14 is connected to the anchoring bolt 9 through the medium of a securing element, referred to generally by the reference character 18 and which consists of a circular head or body portion 19 and a shank comprising an upwardly extending inclined inner portion 20 and a threaded outer portion 21 disposed in a plane parallel

to the plane of the head 19. The outer portion 21 extends through the opening 16 and carries a pair of washers 22 and a pair of clamping nuts 23. Each of the washers is positioned against the inner face of the clamping nut and further abuts against one face of the web 15. The nuts 23 threadedly engage with the outer and inner parts of the outer portion 21 of the shank of the securing element.

The head 19 of the securing element 18 is seated on the chair 5 in proximity to its inner end and is formed with an opening for the passage of the bolt 9. Mounted on the bolt 9 and interposed between the head 19 of the securing element and the head 10 of the bolt 9 is a washer 24. The head 19 of the securing element is of a diameter greater than the diameter of the washer 24 and the latter projects from the head 10 of the bolt 9.

A combined rail anchor, chair and cushion for use with reinforced concrete cross ties, in accordance with this invention not only provides a chair for the track rail, but also a satisfactory cushion therefor, as well as includes means for securely anchoring the track rail with the concrete cross tie, and it is thought that the many advantages of a device, in accordance with this invention, and for the purpose set forth, can be readily understood, and although the preferred construction is as illustrated and described, yet it is to be understood that changes in the details of construction can be had which will fall within the scope of the invention as claimed.

What I claim is:—

1. A device for the purpose set forth comprising a cushioning element adapted to be mounted in and of a height to project above a concrete cross tie, an inverted channel-shaped chair mounted on said element and of a height to overlap the latter and the sides of the cross tie, a securing element provided with a head mounted on said chair and further including an offset outer portion extending through the web of a track rail and carrying means engaging the sides of the web for clamping it to said element, a headed anchoring bolt extending through the head of said element, said chair and cushion and adapted to be embedded in the cross tie, and means engaging with the lower end of the

bolt and embedded in the cross tie for coupling the bolt with the latter.

2. A device for the purpose set forth comprising a cushioning element for mounting on a concrete cross tie, a rail chair mounted on said element, a securing element seating on said chair and including an outer portion extending through the web of a track rail, said outer portion carrying means engaging the sides of the web for clamping said element therewith, and means extending through that part of the element mounted on the chair and further extending through the latter and cushion and embedded in the tie for anchoring the track rail in position.

3. The combination with a concrete cross tie provided with a transverse groove opening at the sides of the tie, of a cushioning element mounted in said groove, flush with the sides of the tie and projecting above the top of the latter, an inverted channel-shaped chair mounted on said element and of a height to overlap the latter and the sides of the tie, a securing member including a head seated on said chair and further including an outer portion disposed in a plane parallel to the plane of the head and adapted to extend through the web of a track rail and carrying means engaging each face of the web for clamping it to said member, and means extending through said head, chair and cushioning element and embedded in the tie for anchoring said securing member therewith.

4. A combined rail anchor, chair and cushion comprising a cushioning element adapted to be mounted in the top of a concrete cross tie, a rail chair mounted on said element, a securing member including a shank and a head, said head mounted on said chair, said shank including an inner, upwardly inclined portion and an outer portion extending in a plane parallel to the plane of the head, said outer portion adapted to extend through the web of a track rail and provided with means for clamping the web therewith, and means extending through the head, chair and element and adapted to be embedded in the cross tie for anchoring said member therewith.

In testimony whereof, I affix my signature hereto.

GEORGE ERNEST NAGEL.
